UNITED STATES PATENT OFFICE.

HENRY O. PUTNAM, OF SUNFIELD, MICHIGAN, ASSIGNOR OF ONE-HALF TO
STEPHEN W. PERKINS, OF SAME PLACE.

DESIGN FOR A FORK FOR POTATO-DIGGERS.

SPECIFICATION forming part of Design No. 21,934, dated October 25, 1892.

Application filed August 24, 1892. Serial No. 443,981. Term of patent 7 years.

To all whom it may concern:

Be it known that I, HENRY O. PUTNAM, a citizen of the United States, and a resident of Sunfield, Eaton county, in the State of Michigan, have invented a new, useful, and original 5 Design for a Fork for Potato-Diggers, of which the following is a specification.

This design relates to forks for that class of potato-diggers which are carried in the hands 10 of the operator; and it consists in the novel external shape and appearance represented by the accompanying drawings and herein 15 after described.

Figures 1 and 2 of the drawings represent, 20 respectively, different perspective views of one and the same fork, with its central shank *a* broken off to omit features which form no part of this design. The shank *a* merges into 25 a rounded head portion *b*, from which a se-

ries of main tines project parallel with each other in nearly-straight lines of a flat curve (represented at *c*) about two-thirds of their length and thence extend with relatively-sharp curves *d* to straight or substantially-straight ends, which terminate in flat rounded 25 extremities *f*. From the ends of the head portion *b* a pair of horn-shaped end teeth *g* project, with compound curved lines, downward and away from the main tines.

Having thus described the said design, I 30 claim and desire to patent under this specification—

The design for a fork for potato-diggers, substantially as herein shown and described.

H. O. PUTNAM.
